UNITED STATES PATENT OFFICE.

JOSEPH BOND, JR., OF PHILADELPHIA, PENNSYLVANIA, ASSIGNOR OF ONE-HALF TO CHARLES M. SWAIN, OF SAME PLACE.

SEWING-MACHINE.

SPECIFICATION forming part of Letters Patent No. 245,771, dated August 16, 1881.

Application filed February 28, 1881. (Model.)

To all whom it may concern:

Be it known that I, JOSEPH BOND, Jr., a citizen of the United States, residing in Philadelphia, Pennsylvania, have invented certain Improvements in Sewing-Machines, of which the following is a specification.

My invention relates to improvements in that class of lock-stitch sewing-machines in which a loop of needle-thread is passed over a stationary spool case or shuttle by a rotating hook; and my invention relates to mechanism, fully described hereinafter, by the aid of which a complete stitch is formed while the needle is making one complete stroke or up-and-down movement and the rotating hook is making one rotation.

My invention further relates to certain devices, described hereinafter, for operating and imparting pressure to the presser-bar, the object of the devices being to avoid well-known objections to ordinary presser-bar attachments, and a further object being to afford facilities for operating the presser-bar at a point most convenient for the manipulation of the same.

My invention further relates to certain feeding mechanism.

My invention further relates to a device, described hereinafter, for imparting tension to the spool or shuttle thread as it leaves the spool-case.

In the accompanying drawings, Figure 1, Sheet 1, is a side view of my improved sewing-machine, the frame-work being in section and the operating parts in elevation; Fig. 2, a section on the line 1 2, Fig. 1; Fig. 3, Sheet 2, an inverted plan view of the machine exhibiting the under side of the base-plate; Fig. 4, Sheet 3, an end view of the machine looking in the direction of the arrow 1, Fig. 1; Fig. 5, the same as Fig. 4 after the removal of the front plate and other appliances, the base in this view being in section on the line 3 4, Fig. 1; Fig. 6, a section on the line 5 6, Fig. 1; Fig. 7, a section on the line 7 8, Fig. 1; Fig. 8, Sheet 4, a perspective view of the device for operating the presser-foot; Figs. 9 and 10, perspective views of detached portions of the feed-motion; Fig. 11, views drawn to an en-

larged scale and showing the construction of 50 the spool-case holder; Figs. 12, 13, 14, 15, 16, and 17, views, also drawn to an enlarged scale, of the spool and spool-case; Fig. 17 $\frac{1}{2}$, a perspective view of the take-up hook; and Figs. 18, 19, 20, 21, 22, and 23, Sheet 5, diagrams 55 showing the mode of forming the stitch by the machine shown in the other figures of the drawings.

A preliminary understanding of the main features of the machine may be best obtained 60 by prefacing the description with an explanation of the mode of forming the stitch, as illustrated by the diagrams, Figs. 18 to 23, inclusive.

In all the diagrams, A represents a rotating 65 disk, provided with a hook, a; B, the reciprocating needle-bar, provided with the usual eye-pointed needle; C, the cloth-plate; E, the stationary spool-case, and F a rotating disk, provided with a hook, b. The spool-case is 70 stationary and held in a position eccentric as regards the disk and the circular course of the hook, for a purpose rendered apparent hereinafter.

The needle-thread x passes through a retaining and releasing device, c, consisting of two disks, one pressed against the other, and shown in Fig. 1, the disks being close together in the middle, but diverging toward the peripheries, so that the thread when taking a 80 course between the disks near the middle of the same will be arrested, but will be free when it takes a course near the peripheries of the disks. After passing this device c the needle-thread x passes through an eye, d, on the 85 top of a vertically-adjustable plate, G; thence through eyes d' and d'' in the same plate, and thence through the eye of the needle. In Fig. 18 the hook a of the disk A, which is revolving in the direction of its arrow, has just released a loop of needle-thread between the device c and eye d, and the needle is descending and commencing to pass through the fabric on the work-plate, the disk F meanwhile revolving in the direction of its arrow. In Fig. 19 90 the needle has descended to the limit of its downward movement and has commenced to ascend, thereby forming an incipient loop of 95

needle-thread, the said loop being in a proper position to be seized by the hook *b* of the disk *F*. It should be understood that the needle in descending took up a portion of the slack thread 5 *x*. In Fig. 20 the hook has seized the loop of needle-thread, and as the needle rises this loop is necessarily enlarged; but this enlargement of the loop is not due to the taking up of any slack thread between the device *c* and eye *d*, but to the rising of the needle, which leaves the thread behind to be drawn into the loop, for it is important that there should be no pulling of the thread through the eye of the needle while the said eye is in the fabric. 10 In Fig. 21 the needle has nearly reached the limit of its upward movement, and the loop of needle-thread has been extended and carried nearly over the spool-case, the additional thread required for the enlargement of the 15 loop being derived from the slack between the device *c* and eye *d*, which slack is entirely taken up. A still further distension of the loop is required before it can be entirely carried over the spool-case, and this additional thread is derived 20 from the upper spool, shown in Fig. 1, Sheet 1. In Fig. 22 the loop has been drawn over the nose of the spool-case and released from the hook *b*, the needle is commencing its downward movement, and the hook *a* of the disk 25 *A* is about to seize the thread between the device *c* and eye *d*. As soon as the hook *a* seizes the thread between the device *c* and eye *d* the course of the thread is so changed as to be caught between the disks of the said device *c*, 30 (see Fig. 23,) so that no thread can be derived from the upper spool, the thread demanded by the continued movement of the hook *a* being derived from the slack below the fabric, and the hook not only takes up this slack, but 35 tightens the stitch formed by the interlocking of the needle-thread with the thread from the spool-case. A further and very slight movement of the disk *A* beyond the position shown 40 in Fig. 23 will be followed by the releasing of the loop, as shown in Fig. 18, after which there 45 will be a repetition of the above-described operations in forming another stitch. It should be understood that the hook is so inclined at the back and outer edge that, while it retains 50 the loop until it reaches the position shown in Fig. 23, the hook cannot move beyond that position without releasing the loop, owing to the position of the latter in respect to the hook and to the inclined back of the same. 55 In machines of the class to which my invention relates—that is, in a machine having a rotating hook for carrying a loop of needle-thread over a stationary spool or shuttle—complicated and inconvenient gearing has here- 60 tofore been used for operating the rotating hook, whereas in my machine all such complicated gearing is dispensed with, as the rotating hook makes but one rotation for each up-and-down movement of the needle, such 65 rotation being at a uniform rate of speed, and a complete stitch being made and tightened

on each rotation of the hook. The eccentricity of the spool-case in respect to the circular path of the hook *b* contributes to bring this about, the position of the spool-case being such that 70 the loop of needle-thread can be passed over its nose at a much earlier stage in the rotation of the hook than if said spool-case should be situated concentrically with the path of the hook, and consequently more time is af- 75 fforded for the taking up of the slack thread than in other machines of this class. The position of the needle in respect to the spool-case also contributes to the attainment of the de- 80 sired result, the needle being so situated as to permit the spool-case to occupy the position shown, and to this position is due, as before remarked, the prompt passage of the loop over the spool-case.

It will be seen on reference to Fig. 18 that 85 the line in which the needle reciprocates is considerably to the right of a vertical line drawn through the center of the disk *F*, and to this is due the fact that the hook *b* on the edge of the disk seizes the incipient loop of 90 needle-thread at the right point—that is, as near to the eye of the needle as possible.

It will be understood that different appliances may be used for taking up the slack between the device *c* and eye *d*. A vibrating 95 arm with a hook may, for instance, take the place of the rotating disk and its hook; but the latter are to be preferred, as a rotary motion can be more directly and economically attained than a vibrating motion. 100

Referring to the general construction of the machine, as illustrated in Sheets 1, 2, and 3, *I* is the stationary arm, projecting from a hollow stand, *I'*, which is permanently secured to the base-plate *H*. 105

J is the driving-shaft, having two bearings in the stationary arm, and a supplementary bearing in a plate secured to the rear of the hollow stand, this shaft being provided with fly-wheel, grooved pulley, and a clutch which 110 forms no part of my present invention.

K is the counter-shaft, having suitable bearings on the under side of the bed-plate, this shaft being provided with a crank-wheel, *e*, the pin of which is connected to a duplex crank, 115 *e'*, on the driving-shaft by a rod, *D*, arranged to slide in a guide, *L*, from which project at right angles to the guide-pins *f*, *f*, one on each side of the said guide and at right angles to the rod, the pins being adapted to guides *g*, *g*, 120 secured to the hollow stand *I'*.

The device consisting of the two cranks, the connecting-rod *D*, guide *L*, and guided pins *f*, *f* forms the subject of a separate application for a patent as a mechanical movement. It 125 will, therefore, suffice to remark here that the parallelism of the rod *D* is insured at all times, and the turning of the counter-shaft with that of the driving-shaft must be as certainly simultaneous as though the two shafts were geared together by ordinary cog-wheels. This movement is applicable to many machines, but it is 130

of special importance when viewed in connection with the bed-plate, counter-shaft, and stationary arm of a sewing-machine, for in many machines for special work it is desirable for 5 the stationary arm to be elevated much higher above the base-plate than in other machines, and all that is necessary to accommodate the above - described movement to machines in which the height of the stationary arm from 10 the bed-plate varies is to make the rod D longer or shorter, as the distance between the two shafts may require.

The driving pulley and clutch may be applied to the shaft K instead of to the upper 15 shaft, in which case the duplex crank e^2 must be on the said lower shaft and the single crank on the shaft above.

At the outer end of the stationary arm and forming part of the same is a plate, N, to which 20 is secured a detachable plate, N', of similar size and form, and between these two plates are the guides for the needle-bar B and presser-bar P. In a cross-head on the needle-bar is a curved slot, i, through which passes a crank-pin, j, projecting from a disk, Q, on the driving-shaft, the head of the pin projecting beyond the needle-bar, and to this head is secured the disk A, previously referred to in describing 25 the formation of the stitch, the disk being secured at a point so far from its center that it shall rotate concentrically with the shaft J. It will be understood that there is an opening 30 in the plate N behind the disk to permit the free movement of the crank-pin.

The device for operating the presser-bar P is shown in perspective in Fig. 8, Sheet 4. On the upper end of the bar and projecting therefrom is a plate, R, through the forked end of which passes an elastic or spring shaft, S, on 35 the end of which is an eccentric, k, between the plate and a projection thereon. This elastic shaft has two bearings, one forming a part of the vertically - adjustable pin l, passing through a projection on the stationary arm of 40 the machine, as best observed in Fig. 2, the adjustability being effected in the present instance by threading the pin and adapting it to a threaded orifice in the said projection. The other bearing of the shaft is in the stand I', and the shaft is here furnished with an arm, 45 m, which passes through a slot in the stand and is situated at a convenient point for being manipulated when the presser-foot has to be raised or lowered. When the shaft has been so turned that the eccentric has depressed the presser-bar and brought its foot into contact with the cloth, the shaft serves as a spring to press the foot down on the cloth; and this pressure may be increased or diminished, as circumstances 50 may suggest, by adjusting the bearing l'. The advantage of this device for operating the presser bar and foot will be best understood by referring to the ordinary spiral spring for depressing the presser-bar in ordinary sewing-machines, the effort to raise the bar being resisted by a constantly - increasing rigidity of 55 the spring as the latter is compressed, a defect

which this feature of my invention overcomes, for the higher the presser-foot is raised the less will be the resistance exerted by the spring-shaft; moreover, there is no necessity for turning the presser-bar round so as to be held up, as in some sewing-machines, the eccentric serving to retain the bar in an elevated position. It is advisable, moreover, that the front of the 75 machine should be free from the usual appliances required for raising and releasing the presser-foot, and that the handle for manipulating the same should be within reach of the right hand of the operator.

The peculiar character of the feeding device and its mode of operation may be best explained by reference to the respective views Figs. 9 and 10.

V is the feed-bar, to which a horizontal reciprocating movement only is imparted, and to this bar the arm s is pivoted at t, so that while the arm reciprocates with the bar it can have a vibrating movement in a vertical plane independently of the bar V, the arm having near 90 its outer end a pointed projection or feed-pin, y, passing freely through the horizontal portion 2 of the bar, the upper surface of which portion is on a level with or slightly above that of the cloth-plate and immediately below the 95 presser-foot. During the rearward movement of the bar the arm s is depressed so that its feed-pin y is retracted beneath the surface of the horizontal portion 2 of the bar V; but when the bar has reached the limit of its rearward 100 movement the arm s rises and its pin passes through the fabric, the presser-foot having a longitudinal groove to receive the point of the pin. During the forward movement of the bar the fabric is carried forward by the pin 105 and the desired feed accomplished. The advantage of this feed mechanism is due to the fact that the horizontal portion of the bar V moves with the fabric in feeding, so that there is no drag on the fabric itself. Even when there 110 are several thicknesses of fabric there can be no drag of one on the other, owing to the feed-pin, which penetrates through all the layers.

While different devices may be used for imparting the desired movement to the feed-bar 115 and arm, I will proceed to describe the mechanism which I have adopted for this purpose.

To the under side of the base-plate is pivoted, by means of an adjustable pin, n, the feed-lever, T, which is actuated by two eccentricities, p p', on the counter-shaft, in the following manner: The feed-lever T rests on an arm, U, Fig. 6, which is loosely connected to the under side of the base-plate, the feed-lever being also caused to bear, in the manner explained 120 hereinafter, against a shoulder on the said arm U. One cam acting on one part of this arm tends to reciprocate it horizontally, the other cam acting on the other part of the arm tending to vibrate the same in a vertical plane; 125 hence the outer end of the feed-lever must receive a combined vertical and lateral vibrating movement.

The feed-bar V is arranged to slide in guides

on the under side of the base-plate, its outer end being acted on by a spring, *u*, Fig. 3, the tendency of which is to force the bar in the direction of the arrow, Fig. 5. The end of the feed-lever *T* passes through a slot, *w*, in the pivoted arm *s* and through a slot in the bar *V*. There are two vertical pins or projections, *v v*, on the feed-lever, and these fit snugly between the top and bottom of the slot *w* in the arm *s*, so that the latter can receive a vertical vibrating motion only from the said feed-lever, the slot *w* being too long to permit the arm *s* to be influenced by the horizontal vibration of the lever. The feed-bar, however, has a slot of such dimensions for admitting the end of the feed-lever that it can only receive a horizontal reciprocating movement therefrom, or rather a movement in one direction from the lever and in the other direction from the spring *u*, and it is this spring which maintains the lever in contact with the shoulder, Fig. 6, on the arm *U*.

The spool-case, which is shown in Figs. 12 to 17, Sheet 4, consists of two parts, *W W'*, which may be entirely separable from each other, as shown, or hinged together, the two parts being so dished as to present, when united, a chamber large enough to receive the spool *X*. This spool has two journals in the part *W'* of the case, the pointed journal 4 having its bearing in a block, 5, Fig. 17, which is so acted upon by a spring that the latter will keep the spool in its place, but can be retracted so as to set the journal 4 at liberty and permit the withdrawal of the other journal from its bearing. The spring also tends to force the end 7 of the spool *X* against a face, 8, formed in the part *W'* of the case.

The course of the needle-thread *z* will be best observed in Figs. 14, 15, and 16. It is first passed from the spool through an eye, 9, near one edge of the part *W'* of the case, thence through a channel, Fig. 15, forming a communication between the said eye 9 and a similar eye, 10, through which the thread also passes, and whence it takes a course between the end 7 of the spool and the above-mentioned face 8 of the spool-case, thence through a slot, 11, Fig. 13, and out through an eye, 12.

In many sewing-machines there is a tendency of the thread to pass from the spool and become caught within the case, and this involves the necessity of stopping the machine for the readjustment of the straying thread. I avoid this difficulty by compelling the thread to take the course which it might accidentally take with the above results—that is, over one end of the spool; but I prepare in the spool-case a face between which and the end of the spool the thread receives the desired tension, which is obtained, while any entanglement of the thread is prevented.

The form of the shuttle is too clearly defined in the drawings to render explanation necessary. It will suffice to remark that it has a nose, 3, over which the loop of upper thread is carried by the hook *b* of the disk *F*, as ex-

plained in referring to the diagrams on Sheet 5, the nose 3 having a groove through which the hook *b* can take its course in carrying the loop of needle-thread over the case. The shuttle is held in place by and between a socket, 14, on the bracket *Y*, Fig. 11, and a socket, 15, Fig. 11, on a bar, *Y'*, which is so fitted to the bracket as to be adjustable thereon, a set-screw 75 and thumb-nut being provided for securing the bar after adjustment. The bracket is secured to the under side of the base-plate, as shown in Fig. 1, Sheet 1.

Referring back to the thread-guide *G*, it may be remarked that its vertical adjustability is of importance, for it may be necessary for the rotating hook to take up more or less of the needle-thread, as the thickness of the fabric may suggest; and it will be seen that the nearer 85 the eye *d* of the thread-guide is to the device *c* the greater will be the length of thread taken up.

I claim as my invention—

1. A sewing-machine in which the following 90 elements are combined, namely: first, a fixed shuttle or spool case; second, a uniformly-rotating hook for carrying the needle-thread round the spool-case; third, a reciprocating needle; fourth, mechanism whereby the hook 95 is turned to the extent of one revolution while the needle makes one complete up-and-down movement; and, fifth, a device for taking up the needle-thread, tightening the stitch, and releasing the said thread during one revolution of the hook, all substantially as set forth.

2. The combination of the fixed spool-case and rotating hook of the sewing-machine with thread-guides and a rotating hook, *a*, for taking up and releasing the needle-thread, said 105 hook having an inclined back, as described, whereby the automatic casting off of the loop is effected as the hook rotates, as set forth.

3. The combination, in a sewing-machine, of a reciprocating needle, a hook rotating in a 110 circular path, and a spool-case held in a position eccentric in respect to the said circular path of the hook, and arranged in respect to the needle, all substantially as set forth.

4. The combination of the rotating hook *a*, 115 the thread-guide *d*, and a device, *c*, for automatically releasing and retaining the thread controlled by the hook, substantially as specified.

5. The combination of the fixed shuttle or 120 spool-case, rotating hook *b*, and rotating thread-controlling hook *a* with the adjustable thread-guiding plate *G*, substantially as described.

6. The combination of the slotted needle-bar *B*, the driving-shaft having a disk, *Q*, and the crank-pin *j*, projecting through the slot of the needle-bar and beyond the same for receiving the disk *A*, all being constructed substantially as specified.

7. The combination of the head *N* of the stationary arm of the machine and detachable plate *N'* with the slotted needle-bar, the rotating hook *a*, attached to a disk or arm situated outside the detachable plate and secured

to the pin through the medium of which the driving-shaft operates the needle-bar, all being constructed substantially as set forth.

8. The combination of the presser-bar of a sewing-machine with an elastic rod or shaft provided with an eccentric or cam adapted to the upper end of the said presser-bar, substantially as set forth, and serving as a medium through which the bar may be operated and of imparting pressure to the bar, all substantially as described.

9. The combination, in a sewing-machine, of the presser-bar with an elastic rod or shaft having a cam or eccentric adapted to the said bar, and two bearings for the said shaft or rod, one bearing being adjustable for causing the shaft to exert more or less pressure on the presser-bar, all substantially as set forth.

10. A sewing-machine feeding device consisting of a bar, V, having a portion, 2, on a level with or slightly above the cloth-plate, and a pivoted arm, s, carrying the feed point or points, with mechanism whereby both bar and arm are intermittently reciprocated horizontally and whereby the arm is made to intermittently vibrate vertically, substantially as set forth.

11. The combination of the bar V, the arm

s, pivoted to the same, the vibrating feed-lever T, adapted to slots in the said bar and arm 30 and having an adjustable pivot, all substantially as set forth.

12. The combination, in a sewing-machine, of the counter-shaft K and its two cams, p p', the feed-lever T and its adjustable fulcrum, and the 35 arm U, loosely connected to the bed-plate and serving as a medium through which the movements of the feed-arm are determined, substantially as described.

13. The combination of the rotating hook b 40 with a fixed shuttle having a nose grooved for the reception of the hook.

14. The combination of a spool-case, a spool, and a spring acting on one end of the spool and tending to force the opposite end of the 45 same against a face formed in the case, with thread-guides which direct the spool-thread between the end of the spool and said face, all substantially as set forth.

In testimony whereof I have signed my name 50 to this specification in the presence of two subscribing witnesses.

JOSEPH BOND, JR.
